UNITED STATES PATENT OFFICE.

EDWARD WALSH, JR., OF ST. LOUIS, MISSOURI.

DESIGN FOR SHEET-GLASS.

SPECIFICATION forming part of Design No. 34,842, dated July 23, 1901.

Application filed July 1, 1901. Serial No. 66,782. Term of patent 14 years.

To all whom it may concern:

Be it known that I, EDWARD WALSH, Jr., a citizen of the United States, residing at the city of St. Louis, in the State of Missouri, have 35
invented a certain new and original Design
for Sheet-Glass, of which the following is a
full, clear, and exact description, such as will
enable others skilled in the art to which it ap-
perts to make and use the same, reference
being had to the accompanying drawings,
forming part of this specification, in which—

Figure 1 is a plan view of a portion of a sheet of glass made in accordance with my new and original design, said view representing the reverse side thereof. Fig. 2 is a similar view representing the obverse side, and Fig. 3 is an edge elevational view.

This invention relates to a new and original design for sheet-glass; and it consists in the 20
surface ornamentation thereof, as will hereinafter be more fully described.

In the drawings I have shown a portion of a sheet of glass, one side of which I have designated as the "obverse" side, being config-
ured by parallel rounded corrugations, while 25
the opposite or reverse side of the sheet is configured by raised and depressed portions, forming regularly-arranged squares containing a band of small pyramids and a group of large pyramids in the centers of each square.

The design consists, essentially, of regu-

larly-arranged squares, within the margins of which is a band of small pyramids surround-
ing four pyramids grouped in the center of the square.

35
A sheet of glass ornamented and configured according to my new and original design has an appearance to the observer different from either of the designs on the opposite faces thereof. When the corrugated surface is 40
nearest the observer, the regularity of the regularly-arranged squares containing a band of small pyramids and a group of large pyramids in the centers of each square on the reverse side is destroyed by refraction, so that 45
the convexes of the corrugations are traversed by lights and shades at about right angles to the axes thereof, while in the concaves of the corrugations the regularly-arranged squares containing a band of small pyramids and a 50
group of large pyramids in the centers of each square on the reverse side are better defined.

What I claim is—

The design for sheet-glass, substantially as 55
herein shown and described.

In testimony whereof I hereunto affix my signature, in the presence of two witnesses, this 21st day of June, 1901.

EDWARD WALSH, JR.

Witnesses:

GEORGE BAKEWELL,
F. R. CORNWALL.
